PUMP

Elbert D. Hale, Glasgow, Mont.

Application December 8, 1937, Serial No. 178,816

2 Claims. (Cl. 103—92)

This invention relates to a pump by means of which water and other liquid may be forced upwardly to an elevated place of use from a source of supply.

5 One object of the invention is to provide a pump of such construction that it is particularly adapted for use in irrigation systems for forcing water upwardly from a well or river or similar body of water to such a height that the water 10 may be delivered to a main irrigation ditch.

Another object of the invention is the provision of a pump of such construction that water is forced by a plurality of impellers into the inlet pipe or neck at the lower end of a vertically disposed column through which the water passes and is discharged through a spout or other suitable outlet at the top of the column.

Another object of the invention is the provision of a pump of this character wherein the 20 impellers are carried by a vertically disposed rotatably mounted shaft extending through a tube from which the inlet pipe of the column extends, the impellers being located above and below the inlet pipe and serving to urge water from opposite ends of the tube towards the inlet neck or pipe of the column. It will thus be seen that one impeller will urge water upwardly through the tube to the neck while the other urges downwardly through the tube to the neck and strain 25 exerted will be such that wear upon a bearing rotatably mounting the lower end of the shaft will be prevented.

Another object of the invention is to provide a pump of this character which is quite simple in 30 construction and consists of a comparatively few number of parts, all of which are strong and durable and not liable to easily get out of order.

The invention is illustrated in the accompanying drawing, wherein

40 Figure 1 is a sectional view taken vertically through the pump, and

Figure 2 is a sectional view taken transversely through the pump along the line 2—2 of Figure 1.

45 This improved pump is particularly adapted for use as means for supplying water to an irrigation system and includes in its construction a column 1 which extends vertically and may be of any height and diameter desired. A discharge 50 spout 2 is provided at the upper end of the column and may extend in any direction desired so that water forced upwardly through the column will flow through the spout and into a trough leading to an irrigation ditch or the spout may 55 overhang the ditch for direct delivery of water

into the ditch. The lower portion 3 of the column is of solid formation to impart weight to this lower portion and cause the column to be firmly supported in its upright position when the outstanding annular flange 4 at the bottom of the 5 column is secured to the base 5 by bolts 6. At the top of the solid portion 3 the column is formed with an inlet from which an inlet neck 7 projects, and referring to Figure 1 it will be seen that the inlet neck communicates with a tube 10 8 midway the length of the tube. This tube 8 extends vertically over a portion of the base which projects from the lower end of the column and since the tube is open at both its upper and lower ends water may enter the tube from both 15 ends for passage in opposite directions through the same to the neck 7 through which it flows into the hollow column.

The water is to be forced through the tube from its opposite ends towards the neck 7, and 20 in order to do so, there has been provided a pump shaft 9 which extends vertically axially of the tube and has its lower end mounted in a bearing 10 carried by the base 5. Spiral blades 11 and 12 are carried by the pump shaft in upper and lower 25 portions of the tube 8, one blade being a right-hand spiral and the other a left-hand spiral. It will thus be seen that, when the pump shaft is rotated, the two impeller blades 11 and 12 will act in opposite directions and force water in end 30 portions of the tube 8 towards its center and from the tube through the neck 7 for passage upwardly through the column. This not only permits water to be fed from both ends of the tube to the neck but also equalizes longitudinal 35 stress upon the shaft and reduces wear upon the bearing 10 and the portion of the shaft engaging the same. Upper and lower bearing brackets 13 and 14 extend from the column 1 at a convenient 40 distance from the level of the water and carry bearings 15 and 16 in which the upper portion of the pump shaft is rotatably mounted. A pulley 17 is firmly secured upon the pump shaft between the bearing brackets for engagement by a belt 18 which serves to impart rotary motion to 45 the pump shaft when a motor engaged by the belt is in operation. There has also been provided a bearing bracket 19 located below the bearing bracket 14 at a point above the water line, and in order to brace the tube 8 and maintain it in a vertical position, there have been provided upper and lower bracing rods 20 and 21. The rods 20 extends through the bracket 19 and carry securing nuts 22 and the rods 21 extend through the base 5 and are provided with secur- 50 55 55

ing nuts 23. When the nuts 22 are tightened, the tube will be firmly braced and prevented from being moved transversely and broken from the neck 7 by force of swiftly running water or 5 by drift wood or the like striking the upper end of the tube.

When this pump is in use, the column is erected in a vertical position in a well, river or other body of water with the tube 8 disposed below the 10 level of the water and the column extending upwardly out of the water. This column may be of any desired height and as water is pumped upwardly through the column it will flow through the discharge spout 2 and directly into an irrigation ditch or through a pipe or trough into the irrigation ditch. It will be obvious that the water need not be used for irrigation purposes but could be pumped into a storage tank or the like. Rotary motion is transmitted to the pump 15 shaft through the medium of the belt 18 and the pulley 17 and as this shaft turns in the bearings 15 and 16 the impellers 11 and 12 will force the water from opposite ends of the tube towards the central portion thereof and through the neck 7 20 into the hollow column through which it flows to the top of the column and out through the discharge spout. The solid lower portion of the column greatly reinforces the same and also imparts weight which will reduce likelihood of 25 the column tilting out of its vertical position.

Having thus described the invention, what is claimed as new is:

1. In a pump, a vertically disposed column having a discharge at its top, a base having the lower 30 end of said column secured thereto with the base projecting laterally from the column, an inlet neck extending from said column, a tube car-

ried by the outer end of said neck and extending upwardly and downwardly therefrom and open at both ends, a bearing carried by the extended portion of the base under the lower end of said tube, bearing brackets extending laterally from said column and spaced one above the other, a shaft extending vertically through said tube axially thereof with its lower end mounted in the bearing of the base and its upper end portion journaled through the bearing brackets, a pulley 10 carried by said shaft, and spirally formed impellers carried by said shaft within the tube above and below said neck, one impeller being of a right-hand spiral and the other a left-hand spiral whereby during rotation of the shaft water may 15 be forced from both ends of the tube towards the center thereof and through the neck into the column and upwardly through the column to the discharge at the top thereof.

2. In a pump, a base, a vertically disposed 20 column rising from said base and having an outlet at its top and an inlet neck extending laterally thereof from adjacent its lower end, a tube disposed vertically in spaced relation to said column and open at its top and bottom, said neck 25 communicating with the tube intermediate the length thereof, a bearing bracket extending laterally from said column over said tube, bracing rods extending vertically from upper and lower ends of said tube and secured through the bearing bracket and the base, a shaft extending vertically through said tube and rotatably supported by the base and the bearing bracket, propellers carried by said shaft above and below the neck, and means for imparting rotation to said shaft. 30 35
